Ohio, a corporation of Ohio

Application March 9, 1935, Serial No. 10,131

13 Claims. (Cl. 120—29)

Our invention relates to that class of inventions which are described in United States Letters Patent No. 1,958,743, issued May 15, 1934, to R. L. Connor et al. This accounting device is 5 designed to be used to expedite the work of accounting where it is desirable to carry a series of compilations across a number of columns for the purpose of obtaining a total. The data to be totalled is usually placed upon paper ribbons. 10 These ribbons are provided with a plurality of perforations at their tops so that they may be held upon pegs and they are generally mounted in shingled relation. A movable line finder is provided to guide the eye across the various columns. This in a large measure prevents errors arising due to adding an amount in another line.

Our invention has for its object to provide a mechanism for shifting the paper instead of the line finder.

20 A further object is to provide for shifting mechanism which will move the paper an exact distance, which distance may be predetermined.

In some cases it may be found desirable to type or write the data which is to be totalled on every other line for greater legibility or any other desired reason.

25 A further object of our invention is to provide means whereby the shifting mechanism may be set so as to shift the papers two lines at a time instead of a single line.

30 The device which holds the paper, when constructed in accordance with our invention, is moved by means of a plurality of belts which are wound upon drums or pulleys rotated by the shifting mechanism. Obviously if these belts were 35 permitted to overlap on the pulley or drums upon which they are wound, the resultant effect would be to increase the diameter of them by an amount equal to twice the thickness of the belts and this 40 would throw the shifting mechanism completely out of alinement.

45 A further object is to so locate the winding mechanism that it will automatically compensate for the increased diameter of the winding drums.

50 A further object of our invention is to provide means to aline the lines on the various ribbons of paper with the line finder.

In some cases it may be found desirable when 55 the paper ribbons have been attached to the clamping device and the ruled lines are slightly above or below the line finders to have means to overcome this difficulty.

A further object of our invention is to provide 55 a micrometer adjustment for the paper with rela-

tion to the line finder so as to move it either up or down until the line finder registers precisely with the lines ruled on the paper.

Our means of accomplishing the foregoing objects may be more readily understood by having reference to the accompanying drawings, which are hereunto annexed and are a part of this specification, in which—

Fig. 1 is a front elevation with a portion of the papers torn away;

Fig. 2 is a perspective view showing the paper partially lowered;

Fig. 3 is a rear elevation with a portion of the covering broken away to show the interior construction;

Fig. 4 is an end elevation;

Fig. 5 is an enlarged fragmentary detailed sectional view of the shifting mechanism on the line 5—5 of Fig. 4;

Figs. 6 and 7 are detailed views showing the 20 means for shifting the paper, the mechanism being shown in different positions;

Fig. 8 is an enlarged fragmentary view of 25 ratchet showing means for holding same against movement;

Fig. 9 is a sectional view on line 9—9 of Fig. 7;

Fig. 10 is an enlarged fragmentary view of 30 Fig. 7;

Fig. 11 is a sectional view on line 11—11 of Fig. 10; and

Fig. 12 is a sectional view on line 12—12 of 35 Fig. 7. Similar reference numerals refer to similar parts throughout the entire description.

As shown in the drawings the perforated leaves or ribbons 1 are suspended from a clamping device comprised of pegs 2 which are permanently attached to a lower peg strip 3 and are covered by an upper peg strip 4. This upper peg strip may be connected to the lower peg strip 3 by means of snap or push buttons 5 such as are 40 commonly used for attaching automobile curtains or in any other suitable or convenient manner for detachably securing the two peg strips together.

The peg strips 3 and 4 with the papers or ribbons attached are suspended from the pins 6 which are permanently fastened to terminal clips 7. These clips are attached to the ends of belts 8. These belts 8 are connected to a cross strip 9 which holds them in position. The peg strips 3 and 4 and the cross strip 9 are prevented from lateral movement either to the right or left by turning up the edges 10' of the peg board 10 upon which the papers rest.

In order to conveniently remove the peg strips 3 and 4 together with the paper leaves or ribbons from the peg board, we cut or otherwise form thumb cuts 10" in the edge of the peg board adjacent its upper end.

We provide a line finder strip 11 which has its ends permanently secured to the turned up edges 10' of the peg board by means of pivots 12 which permits it to be swung away from the 10 surface of the board 10.

The upper end of the peg board 10 is bent rearwardly on an approximate right angle for stiffening purpose. The ledge thus formed serves to provide a support upon which may be fastened brackets 13 at the right and left sides thereof. These brackets 13 support a shaft or rod 14. Upon the rod 14 are rotatably mounted idler pulleys 15 over which the belts 8 pass. In the base of each bracket 13 is a forwardly extending projection 60, the forward ends 60' of which are bent downwardly to provide stops, the purpose of which is to limit the extreme upward travel of cross piece 9 to prevent it from riding up over the idler pulleys 15 and they also serve 25 to position the peg strips 3 and 4 in register with the thumb cuts 10" which are provided for the convenient removal of the paper clamping device from the pins 6.

The operating bar 16 is preferably cast or 30 formed with a stud 17 (Figs. 6-7) upon which pivots a bearing plate 18. This bearing plate swings upon a shaft 19. This shaft 19 is arranged to extend beyond the full width of the device. The shaft 19 is preferably supported at 35 both ends in right and left hand walls 20 of the cover or casing which encloses the mechanism.

These end walls are spaced by means of connecting rods 24 and are securely attached to the peg board by means of angle strips 21.

40 Rigidly fastened to the shaft 19 is a ratchet wheel 22 and adjacent thereto are mounted the flanged driving pulleys or drums 23, one being located at each side corresponding to the idler pulleys 15.

45 Normally, the operating bar 16 is retained in its upper position in contact with a stop pin 51 by means of a tension spring 27 which is located on the rear end of the operating bar and opposite the pivot bearing 17. Spring 27 is attached 50 to an arm 28 which is fixedly secured to a pivot 26 upon which is swingingly mounted a ratchet pawl 25. The other end of this spring 27 may be suitably secured to a pin 29 which is preferably riveted to the left side wall 20. The pivot 55 26 upon which the ratchet pawl 25 is swingingly mounted is located in the extreme rear end of the operating bar 16. This pawl is provided with an upper tooth 25' for contacting with the face of the teeth of the ratchet wheel 22 and operates 60 to intermittently drive the ratchet wheel in a clockwise direction. The amount of movement is positively limited by engagement of the lower tooth 25' with the butt face of the teeth of the ratchet wheel 22.

65 Means are provided to hold the pawl 25 in contact with the ratchet wheel 22 through the medium of a tension spring, one end of which is secured to a pin 48 fixedly mounted in the pawl 25, the other end being attached to a pin 49 in 70 the operating bar 16.

75 Means are provided for removable retention of the ratchet wheel 22 when the pawl 25 is lowered to engage in another tooth. These means comprise a small roller 31 which is held in contact with the teeth of the ratchet wheel 22 by

means of a tension spring 32. The roller 31 is carried by a swinging arm 33 which is suitably attached to the frame plate 18. As illustrated it is secured on a pivot 34 mounted upon the said frame plate. One end of the spring 32 is 5 attached to a pin 35 fixedly mounted in the swinging arm 33, its other end being secured to a pin 36 which is fixedly mounted in the lever 31.

Means for rotating the shaft 19 consist of a crank handle 38 fixedly attached at the extreme 10 right hand projecting end of the shaft 19. This provides for the manual rotation of the ratchet wheel 22 and pulleys or drums 23, in either direction for the purpose of rapidly raising or lowering the papers a number of lines from the 15 top or bottom or vice versa.

To release the retention roll 31 and also the ratchet pawl 25 from engagement with the ratchet wheel 22, during this operation, we provide a release lever 37 which is pivoted on a pivot 20 or pin 45. A release knob 39 projects through a slot in the left hand wall 20 when it is removed to its extreme rearward position it engages a flat spring 40. This operates to force the rounded end of a detent pin 41 into a detent hole 42 25 formed in the bearing plate 18. Two other detent holes are provided, the purpose of which will be hereinafter explained. The lower terminal margin of the release lever 37 is fashioned 30 in the form of a cam which contacts with a roller 43 located on the pin 35 being retained thereon by the end of the spring 32, the end being looped over the said pin 35. When the release lever 37 is moved by means of the knob 39 to the position 35 illustrated in Fig. 7 the high part of the cam bearing on the roller 43 will actuate the arm 33 on its pivot 34 and cause the retention roller 31 to disengage with the teeth of the ratchet wheel 22. The release lever 37 is connected to the ratchet pawl 25 by means of a connecting link 44 40 which is pivoted on the stud 45 which is fixedly secured to the release lever 37. The opposite end of this link 44 is provided with a slot 46 through which passes a pin 48 to which the spring 47 is secured. This slot permits the movement of the 45 pawl when it travels from the top to the bottom of the teeth in the ratchet wheel 22. It will be apparent from this description that movement of the release lever 37 towards the position indicated will cause the connecting link 44 50 to disengage pawl 25 from the teeth of the ratchet wheel 22.

Our means for providing the double line spacing comprise a detent hole 42 which is located directly under the pin 41 as shown in Fig. 6. In 55 this position when the tension of the spring 27 draws the rear end of the operating bar downwardly the inside end of the slot 46 in the link 44 will move to a position which will permit the tension of the spring 47 to pull the tooth 25' of 60 the pawl 25 into contact with the face of one of the teeth on the ratchet wheel 22, two spaces below the ratchet tooth contacted by the pawl tooth 25' when the rear end of the operating bar is in its upper position. This position of the 65 pawl is indicated by means of dotted lines in Fig. 6.

In order to obtain single line spacing the release lever 37 is set in the intermediate hole 50 70 in which position the inner end of the slot 46 formed in the link 44 will prevent the upper tooth 25' of the pawl 25 from contacting the ratchet wheel although the operating bar 16 at this end will lower the same distance as when 75

the double line spacing is desired. As illustrated in Fig. 7 the pawl 25 is positioned to carry the second tooth which will contact one tooth below the extreme upper position. Our means of providing for the micrometer adjustment to enable the operator to shift the position of the paper when the lines thereon do not coincide with the line finder guide is clearly seen in Figs. 6 and 7. When the paper ribbons have been secured to the clamping device it is mounted upon the pins 6, it may be that when this is done, the ruled lines will be shown either slightly above or below the line finder guide 11. This necessitates some means for adjusting the paper minutely but accurately. We accomplish this in the following way:

We provide a knob 52 suitably and fixedly attached to a shaft 53 which is mounted to rotate in a block 54. This block is rigidly attached to the side wall 20. The shaft 53 is limited in end motion by means of collars 55 which are mounted each side of the block 54, the larger diameter of the shaft 53 is threaded into a swivel 56 with a right hand thread. This swivel 56 is provided with a neck or stem which passes through an opening formed in the bearing plate 18 and is held in position by means of a nut as clearly seen in Fig. 9. Rotating the knob 52 to the right, therefore, causes the frame plate 18 and its assembled parts to move around the shaft 19 toward the front of the device, and, because of the contact of the roller 31, causes the ratchet wheel and pulleys to travel with it thus unwinding the belts and lowering the paper clamping strips by gravity over the face of the peg board. Obviously, the operation of the knob 52 in an opposite direction will wind the belts, thus elevating the paper assembly.

The operation of the device is as follows: The distance which the paper moves under the line finder 11 with each downward stroke of the operating bar 16 is obviously governed by the number of teeth in the ratchet wheel 22 together with the diameter of the winding pulleys or drums 23 and although this movement usually corresponds to the line ruling on the paper of six spaces of an inch it will be obvious to persons skilled in the art that movement which will accommodate various other spaces may be readily obtained by substituting the ratchet wheel 22 or the pulleys 23 or both of them for others of different diameters and different numbers of teeth.

When the ribbons of paper 1 are of greater length than the circumference of winding drums 23 more than one turn of these pulleys or drums 23 will be required to move the paper its entire length. Now if we were to permit the belts 8 to overlap after one complete turn of the pulley or drums 23 the working diameter of them would obviously be increased to an amount equal to twice the thickness of the belts and consequently the alignment would be thrown out. We avoid this by locking the pulleys or drums 23 upon the shaft 19 in an offset relation to the idler pulleys 15. In this manner we produce at the rotation of the drums 23 a helical winding of the belts 8 and thus entirely prevent their overlapping regardless of the number of rotations.

To prepare the papers for use on the peg board the lower peg strip 3 may be placed upon a suitable flat desk or table and the ribbons or leaves of paper 1 are attached from right to left in overlapping or shingled relation by placing the upper perforated margin over the pins 2. The upper peg strip 4 is then placed over the paper

and attached to the lower peg strip by means of the snap buttons 5.

The release knob 39 is set temporarily for "release" and by the rotation of the crank 38 the cross piece 9 will be raised to the top of the peg board. The release knob is then set for either single or double spacing for the purpose only of engaging the retention roller 31 in the teeth of the ratchet wheel. The line finder 11 is then swung upon its pivots to an elevated position in which position the paper may be freely passed under the line finder guide. The peg strips are hung from the pins 6 on the right and left hand sides of the peg board and the paper strips are passed intermediate the line finder and the peg board 10. The knob 39 is again set at release and the paper lowered by gravity or by operation of the crank handle 38. The release knob 39 is now set for the required single or double spacing and the top line of the paper is adjusted to the line finder guide 11 by operation of the bar 16 and the knob 52.

Having described our invention what we regard as new and desire to secure by Letters Patent is:

1. In a device of the character described, adapted to carry a plurality of ruled papers; a clamping device from which they are suspended, a line finder which extends across said paper, belts each having one end secured to said clamping device, the other ends being secured to winding drums, a shaft on which said drums are fixedly mounted, said drums being so located that when rotated they will wind the belts in a helix, manually operated means to automatically rotate said drums a predetermined distance thereby shifting the paper with relation to the line finder.

2. In a device of the character described, adapted to carry a plurality of ruled papers; a clamping device from which they are suspended, a line finder which extends across said paper, belts each having one end secured to said clamping device, the other ends being secured to winding drums, a shaft on which said drums are fixedly mounted, said drums being so located that when rotated they will wind the belts in a helix, a ratchet wheel mounted on said drum shaft, a pawl which engages the teeth of said wheel, an operating bar in arrangement to actuate said pawl and thereby intermittently rotate said ratchet wheel.

3. In a device of the character described, adapted to carry a plurality of ruled papers; a clamping device from which they are suspended, a line finder which extends across said paper, belts each having one end secured to said clamping device, the other ends being secured to winding drums, a shaft on which said drums are fixedly mounted, said drums being so located that when rotated they will wind the belts in a helix, a ratchet wheel mounted on said drum shaft, a pawl which engages the teeth of said wheel, an operating bar in arrangement to actuate said pawl and thereby intermittently rotate said ratchet wheel, and means to vary the amount of said rotation.

4. In a device of the character described, adapted to carry a plurality of ruled papers; a clamping device from which they are suspended, a line finder which extends across said paper, belts each having one end secured to said clamping device, the other ends being secured to winding drums, a shaft on which said drums are fixedly mounted, said drums being so located that when rotated they will wind the belts in a helix,

5 a ratchet wheel mounted on said drum shaft, a pawl which engages the teeth of said wheel, an operating bar in arrangement to actuate said pawl and thereby intermittently rotate said 5 ratchet wheel, means to vary the amount of said rotation, and means to prevent rotation of said drum when the position of the pawl is being shifted.

10 5. In a device of the character described, adapted to carry a plurality of strips of ruled paper; a clamping device from which they are suspended, a line finder which extends across said papers, manually actuated means to automatically shift said clamping device and paper a pre- 15 determined distance, and means to adjust the position of either end of said clamping device.

15 6. In a device of the character described, adapted to carry a plurality of ruled papers; a clamping device from which they are suspended, 20 a line finder which extends across said paper, belts each having one end secured to said clamping device, the other ends being secured to winding drums, a shaft on which said drums are fixed- 25 ly mounted, said drums being so located that when rotated they will wind the belts in a helix, a plurality of idler pulleys over which said belts pass, and a shaft on which said pulleys rotate.

25 7. In a device of the character described, adapted to carry a plurality of ruled papers; a 30 clamping device from which they are suspended, a line finder which extends across said paper, belts each having one end secured to said clamping device, the other ends being secured to winding drums, a shaft on which said drums are 35 fixedly mounted, said drums being so located that when rotated they will wind the belts in a helix, a plurality of idler pulleys over which said belts pass, and a shaft on which said pulleys rotate, and means to adjust the position of said idler 40 pulleys radially.

35 8. In a device of the character described, adapted to carry a plurality of ruled papers; a clamping device from which they are suspended, a line finder which extends across said paper, 45 belts each having one end secured to said clamping device, the other ends being secured to winding drums, a shaft on which said drums are fixedly mounted, said drums being so located that when rotated they will wind the belts in a helix, 50 manually operated means to automatically rotate said drums a predetermined distance thereby shifting the paper with relation to the line finder, and means to prevent said drums from unwinding.

55 9. In a device of the character described, a board having upturned edges and a rearwardly 60 extending flange at its top, walls on the end of said board, connecting rods to space said walls, means to secure said end walls to said board, a clamping device adapted to carry a plurality 65 of ruled papers, a line finder which extends across said paper, belts each having one end secured to said clamping device, the other ends being secured to winding drums, a shaft on which said drums are fixedly mounted, said drums being so located that when rotated they will wind the belts in a helix, manually operated means to automatically rotate 70 said drums a predetermined distance thereby shifting the paper with relation to the line finder.

75 10. In a device of the character described, a board adapted to carry a plurality of ribbons of ruled paper arranged in shingle relation, said ribbons having a plurality of clamping peg strips, a plurality of pegs in the lower strip adapted to register with the perforations in the ribbons of

paper, there being corresponding apertures in the upper peg strip, means to detachably secure said strips to each other to clamp the ribbons of paper, a line finder which extends across said ribbons, belts each having one end secured to said peg 5 strips, the other ends being secured to winding drums, a shaft on which said drums are fixedly mounted, said drums being so located that when rotated they will wind the belts in a helix, a ratchet drum mounted on said drum shaft, mechanism to shift said ratchet wheel, a bearing plate which supports said mechanism, and a micrometer adjustment to shift said plate. 10

15 11. In a device of the character described, a board adapted to carry a plurality of ribbons of ruled paper arranged in shingled relation, said ribbons having a plurality of perforations adjacent their upper ends; there being a pair of notches in the edge of said board adjacent its top; a pair of clamping peg strips, a plurality 20 of pegs in the lower strip adapted to register with the perforations in the ribbons of paper, there being corresponding apertures in the upper peg strip, means to detachably secure said strips to each other to clamp the ribbons of paper, a line finder which extends across said ribbons, 25 belts secured to the ends of said clamping strip, pulleys on which said belts are wound, a shaft on which said pulleys are fixedly mounted, an adjustable bearing plate, manually actuated means to shift said peg strips and attached ribbons a predetermined distance, said means comprising a threaded shaft at right angles to the pulley shaft, a block on which the end of said shaft is rotatably mounted, means to prevent the longitudinal movement of said threaded shaft, a swivel on said threads, means to pivotally connect said swivel to said bearing plate, whereby its position may be shifted, and means which permit said paper to shift by gravity. 40

45 12. In a device of the character described, a board adapted to carry a plurality of ribbons of ruled paper arranged in shingled relation, said ribbons having a plurality of perforations adjacent their upper ends; there being a pair of notches in the edge of said board adjacent its top; a pair of clamping peg strips, a plurality 50 of pegs in the lower strip adapted to register with the perforations in the ribbons of paper, there being corresponding apertures in the upper peg strip, means to detachably secure said strips to each other to clamp the ribbons of paper, a line finder which extends across said ribbons, manually actuated means to shift said peg strips and attached strips of paper, a belt secured to the ends of said clamping strips, pulleys on which 55 said belts are wound, a shaft on which said pulleys are fixedly mounted, a crank on one end of said shaft whereby said pulleys may be rotated, means to detachably secure said peg strips to said belts, and means which permit said paper to shift by gravity. 60

65 13. In a device of the character described, a board adapted to carry a plurality of ribbons of ruled paper arranged in shingled relation, said ribbons having a plurality of perforations adjacent their upper ends; there being a pair of notches in the edge of said board adjacent its top; a pair of clamping peg strips, a plurality 70 of pegs in the lower strip adapted to register with the perforations in the upper peg strip, means to detachably secure said strips to each other to clamp the ribbons of paper, a line finder which extends across said ribbons, said line finder being pivotally secured to the edges of the board 75.

whereby it can be swingedly spaced from said paper, a ratchet wheel secured to one of said pulleys, a bearing plate, a pawl carried on said bearing plate which engages the teeth of said ratchet, manually operated means to draw said pawl a predetermined number of ratchet teeth, a micrometer adjustment to shift the position

of said bearing plate, and means which limit the upward movement of said peg strips, said means adapted to cause the ends of the peg strips to register with the notches in said board.
